UNITED STATES PATENT OFFICE.

CLYDE B. LOVELAND, OF BUFFALO, NEW YORK.

KEY FASTENER.

Application filed March 5, 1923. Serial No. 622,761.

To all whom it may concern:

Be it known that I, CLYDE B. LOVELAND, a citizen of the United States, residing in Buffalo, in the county of Erie and State of New York, have invented new and useful Improvements in Key Fasteners, of which the following is a specification.

This invention relates to a fastener or retainer whereby the key of a lock is prevented from being turned from the outside of a room or building and thus preventing unlawful entrance into the same.

It is the object of this invention to provide a fastener of this character which is comparatively simple and inexpensive in construction, which operates efficiently to hold the key against turning when in use, and which is so constructed that the parts thereof are maintained in an assembled position and still permits of conveniently and easily applying the key retainer or fastener to and removing the same from the shank of the door knob.

In the accompanying drawings: Figure 1 is a fragmentary perspective view of a door showing its lock and provided with my invention for preventing the key from being turned from the outside of the door. Figure 2 is a vertical section of the same taken transversely through the shank of the door knob.

Similar characters of reference refer to like parts in both views.

In the drawings my invention is shown in connection with a lock 10 which is mounted on the door 11 provided with a locking bolt 12 and a latch 13. The latch is adapted to be turned by the door knob 14 arranged on the inner side of the door and operatively connected with the latch shifting mechanism of the lock by a shank 15 and the locking bolt is adapted to be projected into and retracted out of its operative position by a key the stem 16 of which is passed through the key hole 17 of the lock on the inner side of the door and has its eye or handle 18 arranged below the shank of the door knob.

My improved key fastener or retainer comprises a carrier which is supported on the shank of the door knob and a keeper which is movable on the carrier into and out of engagement with the eye of the key. In the preferred construction the carrier is formed of a piece of spring wire which is bent into the shape of an inverted letter U, the bow or cross piece 19 of which is adapted

to engage the upper side of the door knob shank while the legs 20, 21 of this carrier extend downwardly from the bow on opposite sides of the shank so that the carrier is suspended or hangs from the shank and has its legs arranged on opposite sides of the key stem.

The keeper is preferably constructed of a single piece of sheet metal so as to form an upper horizontal head or flange 22 and a downwardly tapering tongue 23 arranged at the front edge of the head. At its opposite ends the head is provided with openings 24, 24 which receive the legs of the carrier. By sliding the keeper upwardly on the carrier its tongue is disengaged from the eye of the key whereby the latter may be turned from the inside of the room for locking or unlocking the door. If it is desired to hold the key against turning after the door is locked, the keeper is lowered on the carrier and its tongue is passed downwardly into the eye of the key, as shown in Fig. 1, whereby the latter is prevented from turning and thus prevents operation of the lock by tampering with that part of the key within the lock from the outer side of the door and thus frustrating unlawful entrance into the room. The legs of the carrier are preferably under lateral tension by spreading the same apart a sufficient extent before slipping the keeper thereon so that the tension of these legs will hold the keeper frictionally either in its elevated inoperative or its depressed operative position, as desired.

For the purpose of permitting the carrier to be attached to and removed from the shank of the door knob and still maintain a connection between the carrier and keeper so that the entire fastener is always available when required, one of the legs of the carrier is provided at its lower end with a stop 25 which prevents the head of the keeper from sliding downwardly off the same but the lower end of the other leg is unprovided with a stop and instead is of uniform diameter throughout its length. It is thus possible by this construction to lower one end of the head of the keeper until it strikes the stop thereon and then the other end of the head can be readily disengaged from the lower end of the other leg, to permit the carrier to be passed over the shank of the door knob and then confined therein by engaging the head of the keeper with the lower end of the blank leg. Although the

- stop 25 may be produced in various ways, the same is preferably formed integrally with the respective leg of the carrier by pinching or squeezing the same on its opposite sides so that the metal of this leg is spread outwardly beyond opposite sides of the body of this leg in the form of two lugs which serve as a stop for the keeper, as shown in the drawings.
- 10 This key fastener aside from serving to effectively prevent intrusion into a room from the outside of the same by manipulating the key in the lock, as is frequently attempted, the same is also very simple and 15 inexpensive in construction, and separation of its parts is prevented so that one or the other is not likely to be lost or misplaced.

I claim as my invention:

1. A key fastener comprising a carrier 20 constructed of spring wire in the form of an inverted U and adapted to engage its bow with the top of the shank of a door knob while the legs of the same hang on opposite sides of said shank, the lower end of 25 one of said legs being provided with a stop while the lower end of the other leg is unprovided with a stop, and a keeper slideable vertically on said carrier and having an upper horizontal head which is provided 30 with openings receiving said legs and a tongue projecting downwardly from one edge of said head and adapted to engage with the eye 35 of a key for preventing the latter from turning, one end of said head

being adapted to engage said stop and prevented from being moved downwardly off the same and the other end of the head being free to be slipped off and on the lower end of the other leg for the purpose of enabling the carrier to be applied to and removed from said shank.

2. A key fastener comprising a carrier constructed of spring wire in the form of an inverted U and adapted to engage its bow with the top of the shank of a door knob 45 while the legs of the same hang on opposite sides of said shank, the lower end of one of said legs being provided with a stop while the lower end of the other leg is unprovided with a stop, and a keeper slideable vertically 50 on said carrier and having an upper horizontal head which is provided with openings receiving said legs and a tongue projecting downwardly from one edge of said head and adapted to engage with the eye 55 of a key for preventing the latter from turning, one end of said head being adapted to engage said stop and prevented from being moved downwardly off the same and the other end of the head being free to be slipped 60 off and on the lower end of the other leg for the purpose of enabling the carrier to be applied to and removed from said shank, and said stop being formed on the respective leg by spreading the material of which 65 the same is made.

CLYDE B. LOVELAND.
